UNITED STATES PATENT OFFICE.

GEORGE HENRY WIEMANN, OF NEW YORK, N. Y.

CLOTH-WORKING MACHINE.

1,086,967.

Specification of Letters Patent. Patented Feb. 10, 1914.

Application filed May 8, 1912. Serial No. 695,838.

To all whom it may concern:

Be it known that I, GEORGE H. WIEMANN, a citizen of the United States, and a resident of the city of New York, borough of Brooklyn, in the county of Kings and State of New York, have invented a new and Improved Cloth-Working Machine, of which the following is a full, clear, and exact description.

10 My invention relates to cloth laying machines, and is designed for the purpose of winding or bolting quantities of cloth piled up in folds or layers, each layer being separated from the layer above and below the same by sheets of paper or similar material; and it is so constructed that the sheets of paper or other material in question will be continuously removed by the machine at the same time that the operation of winding or bolting the cloth is in progress.

20 To this end my improved machine comprises a framework having bolting apparatus at one end and an adjustable platform at the other end on which the pile of folded cloth is laid; and the framework also supports other suitable mechanism by means of which the sheets of fabric are properly disposed of without interfering or hindering the operation of bolting or winding the cloth, which it is the function of my machine to perform.

Reference is to be had to the accompanying drawings forming a part of this specification, in which the same characters of reference indicate the same parts in all the views.

Figure 1 is a top plan of my improved cloth laying machine; Fig. 2 is a side elevation of a detail of part of the mechanism for engaging and removing the paper sheets arranged between the folds of cloth; Fig. 3 is a top plan of the parts shown in Fig. 2; Fig. 4 is a side elevation of the means for mounting the guiding rollers of my machine; Fig. 5 is a vertical longitudinal section of my machine; and Fig. 6 is a longitudinal sectional view of the mechanism by means of which the board on which the cloth is bolted by winding is adjustably mounted in position.

50 Referring particularly to the drawings, I construct the framework of my machine so as to include uprights 1, preferably eight in number, four on either side of the same, and these uprights are connected at their

lower ends by means of transverse bars or rods 2. The uprights at the right end of the machine are slotted as shown at 3, to engage a table or platform 4 having a top 5 on which is placed a pile of folded cloth 6. 60 This table or platform 4 is provided with studs or guide pins 7 which project outward from its sides to engage the slots 3, these guide pins being carried by brackets 8 which are preferably formed integral with 65 the table and are arranged at the sides of the front of the same. These brackets 8 have teeth formed along their vertical front edges to provide a rack, this rack being engaged by pinions 10 on a shaft 9, carried in 70 bearings supported by the framework and operated by means of a crank 11. By means of this rack and pinion the height of the top 5 of the platform 4 can be adjusted, and any suitable means can be provided for 75 locking the crank to hold the platform 4 in adjusted position.

The tops of the uprights 1 at the right end of the machine, which may be called the front thereof, are provided with arms 12 80 which extend longitudinally of the framework and have their outer ends connected by means of a bent bar 13. This bar is rigidly mounted on the arms 12 and supports a pair of springs 14 having bearings 85 at their lower ends to receive a roller 15. These springs extend longitudinally of the framework, and the roller 15 rests upon the top of the pile of cloth to keep the folds 90 from moving too rapidly when the machine is in use.

16 is an angle-bar which extends between the uprights 1 at the front of the machine, the vertical portion of this angle-bar resting against the front of the cloth pile, and the horizontal portion being located a little above the top 5 of the platform 4, as shown in Fig. 5. The cloth in the pile 6 is folded back and forth, forming layers, and between these layers are arranged sheets of paper 17, 100 in a manner and for a purpose well known to persons skilled in this art.

The numeral 18 represents an inclined way having the lower edge thereof supported by means of a transverse angle-bar 19, about on a level with the top edge of the angle-bar 16; and its upper edge rests upon a transverse rod 20 passing between the next pair of uprights 1. Part of the sheets of paper between the folds of cloth 110

is carried up this inclined way and delivered into a suitable receptacle adjacent the upper end of the same, when the machine is in use.

5 21 represents a transverse shaft mounted in bearings in the outer ends of the arms 12; and 22 is a transverse bar extending from one of the arms 12 to the other for the purpose of bracing these bars. Similar 10 transverse shafts are arranged in the tops of the first pair of uprights 1, and in the tops of the second and third pairs of uprights as well; and the first two of these shafts 21 have two sprocket wheels 23 each 15 thereon, these sprocket wheels being arranged inside of the posts or uprights 1, and at the opposite ends of the shaft. The last shaft 21 has also a pair of similarly-located sprocket wheels 23 thereon, but the 20 third shaft has two pairs of sprocket wheels, as shown in Fig. 1. The shaft 21 at the top of the second pair of uprights is connected to the shaft 21 at the outer ends of the arms 12 by means of two sprocket chains 26, each 25 of these chains passing over the sprockets 23 at the opposite ends of the shafts, and over and under the sprockets 23 at the top of the first pair of uprights, the upper section of the chain being held in position to engage 30 with the upper side of these last-named sprocket wheels by means of idle rollers 25 mounted on journals 24 in the tops of the first pair of uprights, as Fig. 5 plainly illustrates.

35 The chain 26 comprises a number of ordinary sprocket links, part of which, indicated by the numeral 27, are connected by means of transverse bars 28, from which project teeth 29. These teeth 29 are preferably 40 two in number for each bar, and they are arranged to pass by the ends of the roller 15. These teeth engage the rear edges of some of the sheets of paper 17, and carry them up the incline 18 to deliver them into a suitable receptacle arranged near the upper end of the same. The other pair of sprockets on the third shaft 21 are connected by a second pair of sprocket chains 26 to the sprocket wheels 23 on the fourth shaft 21 45 at the top of the third pair of posts or uprights. This shaft is a power shaft and has on the ends thereof which project beyond the supporting posts 1, a pair of power pulleys 30, over which the belts which furnish the driving power are passed. Beyond the pulleys 30 are two other smaller pulleys 31, which are connected by belts 32 to similar pulleys 31 supported on short shafts 33 carried by the last pair of posts or uprights 1, 50 these last-named pulleys serving to actuate the winding or bolting mechanism of my machine.

The numerals 34 represent guide rollers, two of which are supported by the first pair

of posts 1, one beside the other, just above 65 the upper edge of the angle-iron 16. One of these rollers may have bearings in the post itself and the other on the angle-bar 19. A similar roller 34 is carried by each of the second and third pairs of posts 1; and 34 are 70 similar rollers mounted at their opposite ends in longitudinal bars 35 joining the members of the third and fourth pairs of posts together. Between the last-named rollers 34 is a large roller 34, and it will 75 be seen that the cloth passes over the first roller 34 at the right, and then between the same and the next roller beside it, and then under this last-named roller and the rollers 34 supported by the second pair of posts. It 80 then passes above the roller 34 of the third pair of posts and down under the large roller supported by the longitudinal bars 35. The two rollers 34 at each side of this large roller serve to keep a large portion 85 of the cloth in contact with the periphery of this large roller.

Each of the rollers in question may be mounted in the framework of my machine by means of a spider 36 having a central 90 bearing receiving the journals of the rollers, this spider being mounted so as to support this bearing in alignment with the center of apertures 37 in the posts 1, the object being to support these spiders on the outside of the 95 posts. When one of these bearings wears out, the spider can be removed and another one readily substituted.

The winding mechanism is shown at the left of the frame, and it comprises a board 100 38 on which the cloth is wound or bolted, this bolt being received in the ends of a pair of blocks 39 having receiving recesses 40 into which the board 38 fits. These blocks are rigidly secured to the reduced ends 41 of 105 threaded shafts 42, these threaded shafts being mounted in bearings 43 formed in the upper ends of the last pair of posts 1, and passing outward through these posts and similar bearings 44 which are supported on 110 the outer sides of the same in alignment with the first-named bearings 43. The shafts 42 are threaded over the greater part of their length, but the internal surfaces of the bearings 43 and 44 are not threaded, as plainly 115 shown in Fig. 6. Each of the threaded shafts 42 is provided with a keyway to enable a driving gear 45 to be keyed thereon so as to be able to slide along the same. The bore of the gear is not threaded, so that 120 there is no other engagement between the shaft 42 and the gear 45 except that provided by the spline and keyway above mentioned. The pinion 45 meshes with a pinion 46 rotated by means of the pulleys 31, and 125 47 are handwheels having screw-threaded engagement with the threaded shafts 42 adjacent the reduced ends 41 of the same, these

handwheels being located inside the posts 1 of the framework forming the body of my machine.

The blocks 39 will be located a certain 5 distance apart, according to the width of the cloth and the length of the board on which the same is bolted. When it is desired to move the blocks 39 toward or from each other, no board being in place, the hand- 10 wheels 47 are grasped to make the threaded shafts 42 slide one way or the other in the bearings 43 and 44, the key on the gear 45 moving freely in the keyway in the shafts 42 at this time. When they are about the 15 required distance apart, the board 38 is inserted and the recesses or notches 40 caused to engage the ends thereof. The wheels 47 are then turned until they come in contact with the inner ends of the bearings 43, after 20 which the wheels 47 can be secured against rotation on the shafts 42, by means of a locking screw or in any other suitable way. The rotation of the gears 45 then causes the shafts 42 and the wheels 47, the blocks 25 39 and the board 38 to rotate with them.

In operation, power is transmitted to the 30 pulleys 30, rotating the chains 26 carrying the belt 29 and the bolting board 38. This board draws the cloth off the pile at the front end of the machine, and each alternate 35 sheet of paper, beginning with the sheet on top in Fig. 5, will be engaged by the teeth 29 and carried up the incline 18 to be delivered into a suitable receptacle supported by the framework at the upper end of the trough and above the level of the cloth passing over the rollers 34 also. The other sheet of paper, beginning with the one directly below the uppermost in Fig. 5 will be carried 40 by the folds of cloth through the rollers 34 supported by the first pair of posts 1, and dropped into a suitable receptacle arranged below the cloth between the first and second posts of the framework. Thus the operation 45 of winding or bolting proceeds, and the sheets of paper or the like are automatically removed and deposited in suitable receptacles for receiving the same at the same time. While the operation of winding is in progress, the attendant slowly turns the crank 11, 50 gradually raising the platform 4, so as to keep the top of the bolt of cloth about on a level with the lower end of the inclined way or trough 18.

I wish to have it understood that the 55 above description and drawings illustrate but one embodiment of my invention, and that I do not wish to be limited to the exact details thereof, but reserve to myself the 60 right to make such changes in the shape, size and arrangement of the parts as fairly fall within the scope and spirit of my invention.

Having thus described my invention, I

claim as new and desire to secure by Letters 65 Patent:

1. In a cloth working machine, the combination with its frame of means for supporting a pile of cloth in folds or layers separated by fibrous sheets, means for drawing 70 the cloth off said pile, and means carried by the frame and operated in unison with the drawing means for removing said fibrous sheets as the cloth is withdrawn from the pile. 75

2. In a cloth working machine, the combination of a framework, means carried by said framework for supporting a pile of cloth arranged in folds or layers separated by fibrous sheets, means for adjusting said 80 supporting means to raise and lower the same, and means for automatically removing said sheets and winding or bolting said cloth. 85

3. In a cloth working machine, the combination of a framework, means carried by said framework for supporting a pile of cloth arranged in folds or layers separated by fibrous sheets, a roller adjacent one side of said pile of cloth, and a member separating said pile from said roller, whereby when 90 said cloth is drawn off the pile part of said sheets will pass between the said roller and one side of the cloth. 95

4. In a cloth working machine, the combination of a framework, means carried by said framework for supporting a pile of cloth arranged in folds or layers separated by fibrous sheets, a roller adjacent one side of said pile of cloth, and a member interposed between said roller and said pile of cloth to separate the same, said separating member having an upper edge located below the level of the top of the roller, whereby when the cloth is drawn off the pile over the 100 roller, part of said fibrous sheets will be drawn therewith over the roller between the same and the under side of the cloth. 105

5. In a cloth working machine, the combination of a framework, means carried there- 110 by for supporting a pile of cloth arranged in folds or layers separated by fibrous sheets, means for adjusting said supporting means to raise or lower the same, a pair of rollers carried by the framework adjacent one side 115 of the cloth pile, and a member separating said pile of cloth and said sheets, having an upper edge normally below the top of the rollers, and means for drawing said cloth off the pile over one roller and below the other, whereby part of the fibrous sheets will be drawn by the cloth between the rollers and separated from the cloth. 120

6. In a cloth working machine, the combination of a framework, means carried by 125 said framework for supporting a pile of cloth arranged in folds or layers separated by fibrous sheets, and means carried by said

- framework adjacent said pile of cloth for engaging some of said sheets and removing the same while the cloth is being drawn off said pile.
5. In a cloth working machine, the combination of a framework, means carried by said framework for supporting a pile of cloth arranged in folds or layers separated by fibrous sheets, means carried by said framework above said pile of cloth for engaging some of said sheets to remove the same while the cloth is being drawn from said pile, and an inclined way having one end adjacent said pile over which said sheets are moved after being taken from the pile of cloth.
8. In a cloth working machine, the combination of a framework, means carried by said framework for supporting a pile of cloth arranged in folds or layers with fibrous sheets between them, an incline having its lower end adjacent the top of the cloth pile and to one side of the same, sprocket chains movable above said pile of cloth and said incline, and teeth carried by said sprocket chains to engage part of said fibrous sheets while the cloth is being drawn off the pile and carry them up the incline.
9. In a cloth working machine, the combination with a framework comprising oppositely located slotted posts, and a support having engagement with said slotted posts and adapted to carry a pile of cloth arranged in layers, said support having rack teeth formed along its front edges; of means for drawing the cloth from said pile, means for retaining the lower layers of the cloth on the support, and pinions for engaging said rack teeth to raise and lower the support and correspondingly regulate the position of the pile with respect to the retaining means therefor.
10. In a cloth working machine, mechanism for removing fibrous sheets from piles of cloth arranged in layers having the said fibrous sheets between them, comprising sprocket chains connected by cross-bars, said cross-bars having teeth projecting laterally therefrom to engage the fibrous sheets and carry them off the top of said pile of cloth as fast as the said fibrous sheets are uncovered.
11. The combination of an inclined way, flexible means movable along the sides of said inclined way, cross bars connecting said means, said cross bars having teeth projecting laterally therefrom toward the said way, and means for operating said flexible means.
12. In a cloth working machine, the combination of a framework, means carried by said framework for supporting a pile of cloth arranged in folds or layers separated by fibrous sheets, means for drawing said cloth off of the pile, and means for removing the fibrous sheets from both faces of the cloth as the same is drawn off of the pile.
13. In a cloth working machine, the combination of a framework, means carried by said framework for supporting a pile of cloth arranged in folds or layers separated by fibrous sheets, means for drawing said cloth off of said pile and bolting the same, and means for removing the fibrous sheets from both faces of the cloth as the same is withdrawn from the pile.
14. In a cloth working machine, the combination of means for supporting a pile of cloth arranged in folds or layers separated by fibrous sheets, means for drawing the cloth off the pile, and means associated with the machine and operated in unison with the drawing means to remove the sheet on the top of each of the upper layers by turns as the cloth is drawn off the pile.
15. In a cloth working machine, the combination of means for supporting a pile of cloth arranged in folds or layers separated by fibrous sheets, means for drawing the cloth off the pile, and means associated with the machine and operated in unison with the drawing means for enabling the sheet below each of the upper layers by turns to be removed from said pile as the cloth is drawn off the pile, said means being located adjacent to the pile of cloth.
16. In a cloth working machine, the combination of means for supporting a pile of cloth arranged in folds or layers separated by fibrous sheets, means for drawing the cloth off said pile, and means carried by the machine body above and below the top fold and operated in unison with the drawing means for removing the fibrous sheets above and beneath each of the layers of cloth by turns as the same is withdrawn from the pile.
17. In a cloth working machine, the combination of a framework having oppositely located posts, a table carried by the posts for supporting a pile of cloth, means for adjusting the table vertically and simultaneously shifting the pile therewith, means for withdrawing the cloth from the pile horizontally from the top, and means for exerting pressure on the pile to resist the free release of the cloth as the latter is withdrawn, said means compensating for the adjustments of the table.
